(57) **CLAIM**

The ornamental design for an outdoor thermometer, as shown and described.

DESCRIPTION

FIG. 1 is a front, right side and top perspective view of an outdoor thermometer showing my new design;

FIG. 2 is a front elevational view thereof;

FIG. 3 is a rear elevational view thereof;

FIG. 4 is a left side elevational view thereof; the right side elevational view being a mirror image;

FIG. 5 is a top plan view thereof;

FIG. 6 is a bottom plan view thereof; and,

FIG. 7 is a left side view thereof, with its parts in different positions.

The broken line showing is for illustrative purposes only and forms no part of the claimed design.
